UNITED STATES PATENT OFFICE

135,463

DESIGN FOR A SOAP DISPENSER OR THE LIKE

George H. Packwood, Jr., Glencoe, Mo.

Application June 26, 1942, Serial No. 107,352

Term of patent 14 years

To all whom it may concern:

Be it known that George H. Packwood, Jr., a citizen of the United States, residing at Glencoe, county of St. Louis, State of Missouri, has invented a new, original, and ornamental Design for a Soap Dispenser or the like, of which the following is a specification, reference being had to the accompanying drawing, forming a part thereof, in which:

Fig. 1 is a plan view of a soap dispenser showing my new design;

Fig. 2 is a front view thereof; and

Fig. 3 is a side view.

The side opposite Fig. 3 is symmetrical with that shown in Fig. 3 save for the presence of the handle.

The dominant features of the design comprise the location and shape of the window and the location and shape of the handle in combination with the dispenser bowl.

I claim:

The ornamental design for a soap dispenser or the like, substantially as shown and described.

GEORGE H. PACKWOOD, JR.
